CLAIM

The ornamental design for a touchpad, as shown and described.

DESCRIPTION

FIG. 1 is a front elevational view of the touchpad showing our new design; and,

FIG. 2 is another front elevational view thereof depicting an enlarged portion of FIG. 1.

The broken lines in the drawings show unclaimed subject matter and form no part of the claimed design.

The graded tonality shown in the six upper right rectangles in FIG. 2 is a pattern which is part of the claimed design; the graded tonality could not be shown in FIG. 1 due to the limitations of figure size.
